UNITED STATES PATENT OFFICE.

NEWTON A. ROSE AND ANDREW PRATT, OF FITCHBURG, MASSACHUSETTS.

DESIGN FOR A DUST-PAN.

SPECIFICATION forming part of Design No. 25,666, dated June 23, 1896.

Application filed May 21, 1896. Serial No. 592,482. Term of patent 7 years.

To all whom it may concern:

Be it known that we, NEWTON A. ROSE and ANDREW PRATT, citizens of the United States, residing at Fitchburg, in the county of Worcester and State of Massachusetts, have invented and produced a new and original Design for Dust-Pans, of which the following is a specification.

Our design is embodied in a dust-pan having a pocket or recess for holding the dust, and an inclined front edge which will extend at a suitable angle from the floor or surface upon which the pan may rest.

The accompanying drawing shows a perspective view of a dust-pan embodying our design.

The leading feature of our design consists of a pan-body having a recessed portion or dust-pocket 11, an inclined front edge 10, and a rim which extends around three sides

of the body, as at 12, 13, and 14, said parts being connected by gradual or easy curves which avoid the formation of sharp angles or corners to form lodging-places for the dust or dirt to collect in, and will present a configuration which may be stamped or pressed up out of leather-board or similar material without unduly straining or abrading the same.

What we claim, and desire to secure by Letters Patent of the United States, is—

The design for dust-pans, substantially as shown and described.

In testimony whereof we have hereunto set our hands in the presence of two subscribing witnesses.

NEWTON A. ROSE.
ANDREW PRATT.
